UNITED STATES PATENT OFFICE.

HENRY S. STEBBINS, OF JAMESTOWN, NORTH DAKOTA.

APPARATUS FOR BURNING WEEDS, ETC.

Application filed August 9, 1924. Serial No. 731,065.

To all whom it may concern:

Be it known that HENRY S. STEBBINS, a citizen of the United States, residing at Jamestown, in the county of Stutsman and State of North Dakota, has invented certain new and useful Improvements in Apparatus for Burning Weeds, Etc., of which the following is a specification.

The object of this invention is to provide a weed burner, which, while primarily intended for burning weeds and other growths alongside a railway track, is capable, with only slight modification, of being used similarly for clearing the sides of paved roads, drying baseball fields, or race tracks, melting snow, and like purposes.

The invention comprehends a plurality of burners which burn a spray of oil and air and project a long flame of intense heat, and in this connection, it further contemplates means whereby one or more of the burners may function at a time, with means for confining the flame from a burner to its own locality, so that it will not spread appreciably into the territory of another burner unless it is so desired.

With these and other objects in view as will hereinafter be more fully pointed out, reference will be had to the accompanying drawings forming a part of this specification and wherein like numerals of reference designate corresponding parts throughout the several views, in which:—

Fig. 1 is a view in side elevation of the invention.

Fig. 2 is a top plan view thereof,

Fig. 3 is a view in rear elevation of the invention,

Fig. 4 is a vertical sectional view taken on line 4—4 of Fig. 2.

Fig. 5 is a vertical longitudinal sectional view taken on line 5—5 of Fig. 2 and

Fig. 6 is a detail view in perspective of a fragment of the heat screen.

Referring to the drawings, reference numeral 2 designates the platform of a low flat car set upon inverted channel bars 3 which rest upon the beams 4 constituting the main frame of the car. This main frame is suitably supported upon wheels 5 which travel on the track rails 6.

Extending part way of, or entirely the length of the platform 2, are a plurality of channel beams 7, which, in the plan view, will be seen to be four in number, and these

are rigidly secured to the flat car by suitable clips 8 which are inverted U-shape and straddle the beams 7 and 4. These beams 7 extend rearwardly beyond the rear end of the flat car and cooperating with these projecting portions are parallel shorter channel beams 7^a. To the under faces of the beams 7^a and the projecting portions of the beams 7 is suitably secured a plate 9. Extending downwardly from the plate 9, is a vertical plate 10 which forms the front end of the burner housing, said housing being completed by fixed side plates 12 and rear end plate 14, the plates 9—10—12 and 14 constituting an inverted pan-like housing member within which the flame from the burners 15, to be later described, is confined.

Hinged at its upper edge to each rigid side plate 12 by means of hinges 16, is a plate 17, and similarly hinged along the rigid rear plate 14 are a plurality of plates 18^a, 18^b, the former being disposed between the rails 6 and the latter on the outer sides thereof, and the purpose of these hinged plates or wings 17, 18^a, and 18^b is to close the space between the lower edges of the plates 12 and 14 and the ground, thereby more effectively confining the flame and shielding it from strong winds. The wing side plates 17 extend at their lower edges below the lower edges of the wing rear plates 18^a, 18^b necessitated by the slant of the road bed on both sides so that the weeds can be burned off to the grass or sod line of the road bed.

Hinged at 19 along their upper edges, are plates 20 parallel with and similar to the rigid side plates 12, and these plates 20 serve, when lowered, as partitions to divide the otherwise single burner chamber into four separate compartments.

Extending rearwardly from the rear end plate 14, are a number of arms 21 and between pairs thereof and overlying the track rails 6 are long rollers 22 which extend below the plane of the lower edges of the rigid end plate 14 of the burner housing to engage upon the rails before the lower edges of the rigid end plate 14 can contact therewith, thereby preventing damage to the said end plate or other part of the burner housing through contact of the same with the track rails, as might be caused by any unevenness in the road-bed.

Burners 15 are located between the pairs

of channel beams 7—7^a, there being one burner for each compartment formed by the dropping of the partitions 20, and these burners are of the type which burns oil 5 and air with an intense heat and long flame. These burners are secured in place by gusset plates 24 at an inclination to project the flames at an angle downwardly and rearwardly through openings, not shown, provided in the top plate 9 of the burner housing. The oil is supplied to the burners through pipe 25 leading from the main oil supply to an oil pump 26 from which it is forced through pipe 27 and pipe 28 into 10 transverse pipe 29 having branches 30 which lead into separate transverse pipes 31 having connection with nipples 32 which enter the burner. The pump 26 runs constantly and, therefore, if all the burners are not working, 15 the excess of oil must be led back into the supply reservoir, for which purpose return pipes 33 are provided, the same being in circuit with the main transverse feed pipe 29. An oil pressure gage 34 and pressure 20 regulator 34' are provided in the return line 33.

Air is supplied to the burners 15 through longitudinal upwardly inclined branches 35 leading from a transverse manifold 36, to 30 which a blast of air is fed by a pipe 37 from a rotary compressor or blower 38, which, like the manifold is preferably mounted on the beams 7.

A power plant of the unit type is mounted 35 upon the flat car and includes an internal combustion engine 40, fuel tank 41, (which latter is not the main supply for the burners) and cooling radiator 42. Upon the ends of the power shaft of the engine are secured 40 pulleys 43 and 44, the former being connected to pulley 45 of the blower by means of a belt 46, while the pulley 44 is in driving connection through belt 47 with the pulley 48 of the oil pump 26.

Each hinged side plate or wing 17 is raised and lowered by a chain 60 connected at its lower end to an arm 61 on the plate and the chain then passes over pulley 62, then across the top of the burner housing, 50 around pulley 63, then longitudinally to a hand lever 64, this arrangement being duplicated for each side plate or wing 17. The rear hinged plates 18^a, 18^b, are raised and lowered, each by a chain 66 attached to 55 an arm 61 on the plate and extending vertically to an arm 67, there being three of these arms projecting from a transverse rockshaft 68 journaled in bearing brackets 69. These brackets are, in turn, mounted 60 on a transverse angle bar 70 seated on top of the longitudinal beams 7, 7^a. The rock shaft 68 is provided with another arm 71 from which a link or other desirable connection 72 extends forwardly to a hand lever 73.

The partitions 20 are raised and lowered by a suitable mechanism such as flexible connections 75 and hand levers 76, the latter being preferably adjacent the hand levers 64 and 73.

Because of the intense heat given out by the flames from the burners and which rises from the rear portions mostly of the burner housing, it is preferable to have a heat screen 70 in the nature of a transverse plate 80 extending entirely across the burner housing, set on edge and hinged at 81 to the upper faces of each longitudinal beam 7, 7^a, said screen plate being notched to receive the said beams and having the portions 82 between the 75 notches extending down between the beams to a point adjacent the top plate 9 of the burner housing. Any desired means, not shown, may be employed to hold the heat screen in vertical position, and when not in such position, it is folded down upon the tops of the said longitudinal beams. The purpose of this screen is to shield the operator who stands on the flat car within 80 reach of the aforementioned hand levers.

In operation, the burner unit is attached to the flat car by the clips 8, and this car may either be attached to or form part of a work or other car which preferably carries the main oil supply for the burners and is propelled or self propelling. The entire burner housing will be supported clear of the rails and the ground. The rollers 22 being disposed to engage with the track rails before the housing can contact therewith, will prevent the housing from striking the rails and becoming injured because of any unevenness in the road bed; and when the rollers 22 are engaged with the track rails, straining is further prevented by the fact that the beams 7 can separate slightly from the rear part of the flat car platform and raise because of the single line of connections 8 being at the forward ends of the beams 7. As the car 85 travels along the rails, with the wing plates 17, 18^a, 18^b dropped and one or more of the burners lighted, the flame or flames from the lighted burners will play upon the weeds growing along the track bed and destroy the same. When the car is passing through yards, over switches and the like, the wing plates are all raised to clear the rails and thereby prevent any damaging contact between the plates and rails, but at other times, the wing plates are lowered to protect the flame from the wind and to confine the same since the burners working under great pressure will throw an intense flame well beyond the rear end and even the sides of the burner housing unless the same is confined.

Should it be desired to burn the weeds along the shoulders only, then only the burners overlying the shoulders are lighted, and the outer partitions 20 dropped to confine the flame to the shoulder. If only the weeds be-

tween the rails are to be burned, then only the two center burners are lighted and the same partitions as before are dropped. If only one or the other side of a rail is to be treated, then only the burner on the desired side is lighted, and the appropriate partition dropped to confine the flame to that section, and so on in various combinations as called for by the particular surface burning or heating desired.

The preferred construction and arrangement of apparatus thus specifically set forth may evidently be modified, and its mounting upon a separate or combined car be varied, without departing from the invention as defined in the claims.

What is claimed is:—

1. In a surface heater, the combination with a vehicle, of a housing supported thereby, a plurality of burners arranged to direct flames within said housing, and adjustable means within the housing for dividing the interior of the latter into compartments.

2. In a surface heater, the combination with a vehicle having a running gear frame, of a rearward extension from said frame supported solely thereby and overhanging surface to be heated, a burner mechanism carried by said extension above said surface, and a safety roller carried by said extension clear of said surface and disposed in a lower plane than the burner mechanism to prevent the latter from contacting with said surface.

3. In a surface heater, the combination with a vehicle, of a burner mechanism overhangingly supported thereby above the surface to be traversed, supporting means secured to the vehicle so as to permit upward yielding movement of the overhanging portion thereof, and surface contacting means carried by said overhanging portion in a plane below the burner mechanism but normally above the surface traversed.

4. In a surface heater, the combination with a vehicle, of a burner housing supported by the vehicle above the surface to be traversed, adjustable partitions dividing the housing into successive adjacent compartments, and a burner for each compartment, the burners being supported by said housing.

5. In a surface heater, the combination with a vehicle, of a burner housing supported thereby above the surface to be traversed, a plurality of burners for said burner housing, and means whereby the burner housing may be changed from a single compartment to a plural compartment structure.

6. In a surface heater, the combination with a vehicle, of a burner housing supported thereby above the surface to be traversed, a plurality of burners for said burner housing, and means whereby the burner housing may be changed from a single compartment to a plural compartment structure,

with at least one burner for each compartment.

7. In a surface heater, the combination with a vehicle, of a burner housing supported thereby above the surface to be traversed, hinged partitions within said housing movable to change the same from a single to a plural compartment structure, means for independently moving said partitions, and at least one burner for every compartment to which the compartment may be changed.

8. In a surface heater, the combination with a vehicle, of a burner housing supported thereby above the surface to be traversed, flame confining means carried by said housing and adapted to be lowered into close proximity to the said surface, partitions movable to change the housing from a single compartment to a plural compartment structure, and at least one burner for each of said compartments.

9. In a surface heater, the combination with a vehicle, of a housing member, a series of parallel beams resting on said vehicle and projecting therebeyond and said projecting portions supporting said housing above the surface to be traversed, and burners for said housing supported between said beams.

10. In a surface heater, the combination with a vehicle, of a housing member, beams resting on said vehicle and projecting therebeyond and said projecting portions supporting said housing above the surface to be traversed, a burner for said housing between each pair of beams, and partitions movable to change said housing from a single compartment to a plural compartment structure, with at least one burner for each compartment.

11. In a surface heater, the combination with a vehicle, of a burner housing, beams projecting beyond said vehicle and their projecting portions supporting the burner housing above the surface to be traversed, burners mounted each between a pair of beams at an angle to project their flames downwardly and rearwardly, adjustable division plates disposed intermediate said burners, and means movable to substantially close the space between said housing and said surface to confine the flame.

12. In a surface heater, the combination with a railway vehicle having a running gear frame, of a rearward extension from said frame supported solely thereby and overhanging the surface to be heated, a burner mechanism carried by said extension above said surface, and rail-contact means carried by said extension in a plane below the burner mechanism but normally above the rail surface.

In testimony whereof I affix my signature.
HENRY S. STEBBINS.
